UNITED STATES PATENT OFFICE.

HENRY C. ESSINGTON, OF PHILADELPHIA, PENNSYLVANIA.

ROTARY ENGINE.

SPECIFICATION forming part of Letters Patent No. 727,769, dated May 12, 1903.

Application filed August 13, 1902. Serial No. 119,560. (No model.)

To all whom it may concern:

Be it known that I, HENRY C. ESSINGTON, a citizen of the United States, residing at Philadelphia, in the county of Philadelphia and State of Pennsylvania, have invented a new and useful Rotary Engine, of which the following is a specification.

This invention relates to certain improvements in rotary engines.

One of the principal objects of the invention is to provide an engine that may be readily reversed at any point without regard to the position of the revolving piston and its blades; and a further object is to provide a reversing mechanism by which the direction of flow of steam may be altered and the active exhaust-ports changed by the movement of a single operating-lever.

A still further object of the invention is to provide in mechanisms of this class for controlling the speed and power of the engine by adjusting the positions of the reversing-valves to govern the quantity of steam admitted to the cylinder.

A still further object of the invention is to provide an engine of this type with an exhaust port or ports through which dead steam will be expelled in order to prevent back pressure between the cylinder-abutments and the piston wings or abutments.

A still further object of the invention is to provide the engine with valves for controlling the quantity of steam admitted to the cylinder for actuating the successive piston-wings and to provide a valve-operating mechanism by which the steam-supply may be cut off at a desired point and the steam used expansively.

A still further object of the invention is to reduce friction by making the piston-wings or abutments in the cylinder-abutments in form of rollers.

With these and other objects in view the invention consists in the novel construction and arrangement of parts hereinafter described, illustrated in the accompanying drawings and particularly pointed out in the appended claims, it being understood that various changes in the form, proportions, size, and minor details of the structure may be made without departing from the spirit or

sacrificing any of the advantages of the invention.

In the drawings, Figure 1 is a side elevation, partly in section, of a rotary engine 55 constructed in accordance with my invention. Fig. 2 is a sectional plan view of the same on the line 2 2 of Fig. 1. Fig. 3 is a longitudinal sectional elevation of the engine. Fig. 4 is a transverse sectional elevation on the 60 line 4 4 of Fig. 1, illustrating the construction of the steam-press and the arrangement of the valves. Fig. 5 is a detail perspective view of one of the movable cylinder-abutments detached. Fig. 6 is a similar view of 65 one of the steam-valves.

Similar numerals of reference are employed to indicate corresponding parts throughout the several figures of the drawings.

The cylinder 10 is mounted on a suitable 70 base, and in its opposite sides are stuffing-boxes through which passes a shaft 11, the latter being mounted in suitable bearings of any character and provided with a belt or other wheel by which power will be transmitted to the apparatus to be driven. On the shaft is secured a cylindrical piston-body 12, having peripheral recesses 13, in which are fitted piston-wings 14 in the form of rollers which bear against the inner curved surface 75 of the cylinder and which may freely turn in the support formed by the recessed piston-body. At diametrically opposite points the cylinder is provided with radially-disposed grooves 15, in which are guided transversely-disposed plates 16, having forwardly-extending ears forming supports for a spindle 17, on which is mounted a roller 18, forming a movable cylinder-abutment, said abutment being held against the periphery of the piston and 80 turning freely as the latter revolves. The abutment is held in operative position by steam-pressure, the plate 16 having vertically-disposed flanges 19, against which the pressure of the steam is exerted as it passes 85 into the steam-space of the cylinder, and in addition to this a spring may be employed to assist in holding the abutment in proper position. The abutments are forced outwardly by contact with the piston-wings 14, the 90 rounded surfaces of the latter coming into contact with the roller-abutments and grad-

ually forcing the same out beyond the outer line of the piston-wings and around the surfaces, permitting the gradual return of the abutments to normal position after the piston-wing has passed. The cylinder-abutments are each located within a casing 20, which is divided into upper and lower compartments 21 and 22 by the abutment-plate 16, and the latter, in addition to the sideguides 15, is further guided by the walls of a recess 23, formed in the rear portion of the casing 20, suitable packing-strips being preferably employed in order to prevent the leakage of steam from one compartment to the other. The vertical height of the two compartments is greater than that of the flanges 19, and on reference to Fig. 3 it will be seen that the edges of the flanges are inclined, as indicated at 25, in order that the steam may exert considerable pressure thereon in passing into the cylinder.

At one side of each casing 20 is secured a steam-chest 26, to which steam is supplied through a pipe 27, and said steam-chest is provided with a horizontally-disposed partition 28, dividing it into two chambers, which communicate through ports 29 and 30 with the upper and lower compartments 21 and 22, respectively, of the casing 20. The steam-chest is provided with suitable guideways for the reception of ported valves 31 and 32, which govern the passage of steam through the ports 29 and 30, respectively, and said valves are so connected to an adjusting mechanism that when one is moved to open communication between the steam-chest and one of the compartments the other will be closed, and in this manner steam may be supplied to the upper compartment 21 to cause the movement of the revolute piston in any direction or to the compartment 22 to effect a movement of the piston in the opposite direction. Each steam-chest is further provided with guides for the support of a steam-valve 33 of the peculiar construction illustrated in Fig. 6, said valve being in the form of a plate having recesses cut in its opposite walls in such manner that when the valve is at the limit of its movement in one direction the steam-port 29 will be opened to the cylinder, and at the opposite end the steam-ports 30 will be opened. One of the ports 29 30 is closed at all times, so that the movement of the steam-valve will open communication through but one of said ports.

In one side of the revolving piston 12 is a recess 35, in which are placed a gear-wheel 36 and a pair of pinions 37, the gear-wheel being secured to the main shaft 11 and the pinions intermeshing with said gear and being carried by spindles 38, which project through suitable stuffing-boxes to the outside of the cylinder. To the end of each cylinder is secured an eccentric 39, connected by an eccentric strap and rod 40 to the steam-valves 32, the movement of the parts being timed in

such manner that steam is admitted to the cylinder immediately after one of the piston-wings passes one of the cylinder-abutments and is then cut off after the piston has rotated a desired distance, preferably somewhat less than one-quarter of a revolution, the steam being then used expansively until the next succeeding abutment is acted upon. The main exhaust-ports 40 are disposed at the top and bottom of the cylinder and are at all times open to permit the escape of steam therefrom. The principal portion of the steam will be exhausted through these ports; but under ordinary circumstances, and especially when traveling at high speed, a quantity of steam will remain in the cylinder between the piston-wing and the cylinder-abutment toward which it is moving. Under ordinary circumstances considerable back pressure would result from the compression of the steam between the relatively fixed abutment and the rotating piston-wing, and it would result not only in lessening the effectiveness of the engine, but would increase the friction on the abutment-supports and render it necessary to exercise considerable power to force the abutment outward and allow the piston-wing to pass the same. This difficulty is overcome by the provision of vents 42 and 43, disposed on each side of the cylinder-abutments, and will permit the escape of the dead steam between the abutment and the piston-wing. These vents may be connected by pipes 45 to the main exhaust in order that all of the exhaust-steam may be led to a common point of discharge. The vent-openings lead to the cylinder and communicate with small casings or chests 46, in which are disposed valves 47 and 48, all of said valves being connected to a single adjusting mechanism which may be moved to open either the pair of ports 42 or the pair of ports 43.

To one side of the cylinder is pivoted a reversing and controlling lever 50, carrying a latch 51, which may lock the lever in any one of a series of notches in a rack 53, the lever having three main positions—one in the central position, with the engine stopped and all the steam-supply ports closed, the other two positions serving to close one set of valves and open the opposite set for effecting the rotation of the piston in either direction. The upper valves 47 and 48 of the auxiliary exhaust or vent portions are connected by a rod 54 to the lever 50, the movement of said lever in one direction opening the port 42 and closing the port 43, and vice versa. Pivoted to the outer face of the cylinder at diametrically opposite points are two levers 55 and 56, having pin-and-slot connections with the valve-rod 54 and movable simultaneously in the same direction. The levers are pivoted at a central point and at the lower end are connected, respectively, to the lower valves 48 and 47, which control the exhaust-ports

42 and 42, and on the movement of the operating-lever the exhaust-port 42 of the upper set and the exhaust-port 42 of the lower set will be moved to the same position and the valves of the port 43 moved to the opposite position.

Each of the steam-valves 31 and 32 is provided with a stem extending out through a suitable stuffing-box in the valve-chest, the stems being connected by rods or links 57 to the levers 55 in the manner shown in Fig. 1. The levers 55 have pin-and-slot connections with the valve-rod 54 and are moved simultaneously with the movement of the valve-rod, so that all of the valves controlling the steam and auxiliary exhaust-ports are simultaneously operated. When the reversing-lever 50 is in the position illustrated in Fig. 1, the steam-port 39 at both sides of the cylinder and the steam-port 30 at the opposite side of the cylinder may be opened and the other steam-ports closed, while both of the auxiliary exhaust-ports 42 of the engine will be open and the exhaust-port 43 closed, while a movement of the reversing-lever in the opposite position will reverse the position of all of these valves and cause the piston to rotate in the opposite direction.

In operation, steam being admitted through the upper port 29 at the right-hand side of the engine and through the lower port 30 at the left-hand side of the engine, the piston will revolve, the supply of steam being cut off before the piston-wings on which the pressure is being exerted reach the upper and lower main exhaust-ports. After passing the main exhausts the steam freely escapes, but a small quantity of steam will remain in the steam-space and will be carried on in advance of the wings in the direction of the cylinder-abutment at the opposite side of the engine. As the auxiliary exhaust-ports 42 are open, this steam may escape and all back pressure between the advancing wing and the relatively stationary cylinder-abutment will be avoided, and as there is little or no pressure on the abutment the latter may readily move outward to permit the passage of the wing. In reversing, all of the steam and exhaust valves are simultaneously operated and opportunity afforded for the immediate relief of the pressure through the auxiliary ports thus opened, and while one of the piston-wings will at all times be in proper position to be acted upon by the steam-pressure and effect the reversal of the engine as quickly as momentum can be overcome.

The ports of the valves 47 and 48, which control the auxiliary exhausts, may be made somewhat wider than the port-openings leading to the cylinder in order to permit the movement of the rod 50 to an extent sufficient to partially close the main steam-ports and regulate the quantity of steam admitted to the cylinder, and thus render possible the adjustment of the power in accordance with the speed and load.

Having thus described my invention, what I claim is—

1. The combination in a rotary engine, of the cylinder, a revoluble piston therein, a casing arranged at one side of the cylinder, a radially-movable abutment guided within said casing and serving to divide the latter into two compartments either of which may be placed in communication with the steam-supply, the steam-ports leading from the chambers to the steam-space of the cylinder at points on each side of the abutment, a steam-chest, ports leading from the steam-chest to both chambers, a steam-valve operated by the engine and adapted to uncover both ports, and reversing-valves independent of the steam-valve and movable to permit the passage of steam through one or other of the ports from the steam-chest to one of the chambers.

2. The combination in a rotary engine, of the cylinder, a revoluble piston therein, a movable cylinder-abutment, a casing provided at one side of the cylinder and divided by the abutment into two compartments which respectively communicate with the steam-space of the cylinder on opposite sides of the abutment, a steam-chest having ports leading to both compartments, reversing and cut-off valves for closing or adjusting the area of said ports, and a slide-valve movable to alternately uncover said ports.

3. The combination in a rotary engine, of the cylinder, a revoluble piston therein, a casing disposed at one side of the cylinder and having recessed walls, a radially-movable abutment guided in said recesses and dividing the casing into two compartments each communicating with the steam-space of the cylinder, a steam-chest, ports leading from the steam-chest to both compartments, reversing-valves closing one or other of said ports, and a slide-valve controlling both the ports and adapted to uncover one port at the end of the stroke in one direction and the other port at the end of the stroke in the opposite direction.

4. The combination in a rotary engine, of the piston, a cylinder, a casing connected therewith and provided with abutment-guides, an abutment having a radially-disposed plate adapted to said guides and serving to divide the casing into two compartments, valves for controlling the admission of steam to said compartments, upper and lower flanges disposed on the abutment-plate, and a roller carried by the plate and adapted for contact with the periphery of the piston.

5. The combination in a rotary engine, of the cylinder, a revoluble piston having curved recesses in its periphery, and rollers disposed in said recesses and adapted for contact with the inner circular wall of the cylinder, said rollers forming piston wings or blades.

6. The combination in a rotary engine, of the cylinder, a revoluble piston having peripheral recesses, rollers adapted to the recesses and forming piston-wings, and a roller-

cylinder abutment adapted for contact with the periphery of the piston and movable outwardly by the piston-wings.

7. The combination in a rotary engine, of the cylinder, abutments carried thereby, a piston having radially-disposed wings or blades, steam and exhaust ports for the passage of steam to and from the cylinder, and auxiliary vent or exhaust ports communicating with the cylinder at points adjacent to the cylinder-abutments and open to permit the free escape of dead steam as the piston-wings approach the abutments.

8. The combination in a rotary engine, of the cylinder, abutments carried thereby, a piston having radially-disposed wings or blades, steam and exhaust ports for the passage of steam to and from the cylinder, auxiliary vent or exhaust ports disposed on each side of the abutments, and serving to permit the free escape of dead steam in advance of an approaching piston wing or blade, valves for closing one set of ports and opening the opposite set of ports and means for simultaneously operating said valves, substantially as specified.

9. The combination in a rotary engine, of the cylinder, a casing disposed at each side of the cylinder, movable abutments arranged within said casings, a steam-chest arranged at each side of the cylinder and having ports for communication with said casings, reversing-valves for controlling the flow of steam to the casing on one or other sides of the abutments, auxiliary exhaust-ports formed in the cylinder on opposite sides of each abutment, valves for the auxiliary exhaust-ports, and a single operating-lever connected to all of the reversing-valves and all of the auxiliary exhaust-port valves.

10. The combination in a rotary engine, of the cylinder, a revoluble piston therein, casings disposed at opposite sides of the cylinder and in communication therewith, radially-movable abutments disposed in said casings, steam-chests having port connections with the casings on opposite sides of the abutments, valves for controlling the flow of steam through said ports and reversing the direction of movement of the piston, auxiliary exhaust-ports formed in the cylinder on opposite sides of the abutments, valves for controlling the passage of steam through said ports, a pivotally-mounted reversing-lever, a pair of auxiliary levers pivotally mounted on the cylinder, a valve-rod connecting two of the auxiliary exhaust-port valves to the main operating-lever and to the auxiliary levers, and links connecting said auxiliary levers to the remaining exhaust-valves and to all of the reversing-valves.

11. The combination in a rotary engine, of the cylinder having steam and exhaust ports, a revoluble piston in said cylinder, a shaft carrying said piston, a gear-wheel mounted on the shaft, pinions intermeshing with said gear-wheel, auxiliary shafts or spindles on which said pinions are secured, eccentrics carried by the auxiliary shafts or spindles, steam-valves for controlling the admission of steam to the cylinder, and rods connecting said valves to said eccentrics, substantially as specified.

In testimony that I claim the foregoing as my own-I have hereto affixed my signature in the presence of two witnesses.

HENRY C. ESSINGTON.
